UNITED STATES PATENT OFFICE.

NUGENT MILNER, OF EVANSVILLE, INDIANA, ASSIGNOR TO GRAHAM BROTHERS, OF
EVANSVILLE, INDIANA, A CORPORATION OF INDIANA.

VEHICLE-BODY CONSTRUCTION.

Application filed December 7, 1925. Serial No. 73,740.

This invention relates generally to vehicle bodies and consists of certain novel features of construction, combinations and arrangements of parts as will be more fully described and particularly pointed out in the appended claims.

In the accompanying drawing:

Figure 1 is a perspective view of a construction embodying my invention.

10 Figure 2 is a sectional view taken on the line 2—2 of Figure 1.

Figure 3 is a sectional view taken on the line 3—3 of Figure 2.

15 Figure 4 is a sectional view taken on the line 4—4 of Figure 2.

Referring now to the drawing, the numerals 1, 2, and 3 respectively designate frame members and the numerals 4 and 5 respectively designate outer panels of a vehicle body. As shown, the frame member 1 is provided with laterally spaced recesses 6 and 7 respectively for receiving the adjacent ends of the frame members 2 and 3, while the latter as well as the web 8 provided between the recesses have aligned slots or grooves 9, 10, and 11 respectively for receiving the marginal flanges 12 and 13 respectively of the panels 4 and 5. Thus the panels may be positioned quickly and accurately by the engagement of the marginal flanges 12 and 13 respectively with the aligned slots 9, 10, and 11. Any suitable means such as the screws 14 may be used to secure the frame members 2 and 3 respectively in the recesses 6 and 7.

To provide a neat construction, the panels 4 and 5 are preferably secured together in overlapping relation and are fastened to the frame members by two rows 16 and 17 respectively of nails. As shown, one row 16 of nails extend through the marginal flanges 12 and 13 and engage the frame members 2 and 3, while the other row 17 of nails extend through the panel 4 and engage the frame member 1. To conceal the last mentioned row 17 of nails as well as the joint between the panels, the latter are provided with interlocking return-bent flanges 18 and 19 respectively. As shown, the panel 5 covers the return-bent flange 18, while the return-bent flange 19 is received between the flange 18 and panel 4 and seats against the heads of the nails 17. Thus these nails are prevented from working loose.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. In combination, a frame member having recesses therein, and a web between said recesses, frame members secured in said recesses, said web and last mentioned members having aligned slots, and panels secured to the members aforesaid having flanges received in said slots. 55

2. In a vehicle body, the combination with a frame member having recesses therein, and a web between said recesses, and frame members secured in said recesses, the web and last mentioned members having cooperating means for positioning panels and the like. 60

3. In combination, a frame member having laterally spaced recesses therein, frame members having the adjacent ends thereof secured in said recesses, and adjacent sheet metal panels having interlocking parts secured to the first mentioned frame member and having marginal flanges at each side of said parts secured to the last mentioned frame members. 75

4. In combination, a frame member having recesses in one side thereof, frame members secured in said recesses and having aligned longitudinally extending slots extending transversely and laterally with respect to the first mentioned frame member, and panels overlapping and secured to the last mentioned members and having flanges received in said aligned slots. 80

5. In combination, a frame member having a recess in one side thereof, a frame member secured in said recess and having a longitudinally extending slot in one side thereof extending laterally with respect to the first mentioned frame member and a sheet metal panel overlapping the first and last mentioned frame members and having a positioning flange received in the longitudinally extending slot in the last mentioned frame member aforesaid. 95

In testimony whereof I affix my signature.

NUGENT MILNER.
